UNITED STATES PATENT OFFICE.

EDGAR W. ANTHONY, OF BOSTON, MASSACHUSETTS.

STOVE-GRADE.

SPECIFICATION forming part of Letters Patent No. 293,296, dated February 12, 1884.

Application filed May 14, 1883. (No model.)

To all whom it may concern:

Be it known that I, EDGAR W. ANTHONY, of Boston, in the county of Suffolk and State of Massachusetts, a citizen of the United States, 5 have invented a certain new and useful Improvement of Stove-Grates, of which the following is a full, clear, and exact description, reference being had to the accompanying drawings, forming a part of this specification, in 10 explaining its nature, in which—

Figure 1 is a plan view of a grate having my improved construction. Fig. 2 is an end elevation thereof. Fig. 3 is a vertical section on the line $x-x$ of Fig. 1. Fig. 4 illustrates a 15 modified form of the invention, wherein only the upper portion of the grate is used. Fig. 5 is a vertical section upon the line yy of Fig. 4.

This invention is an improvement upon that described in my Letters Patent No. 229,852, 20 dated July 13, 1880. The especial form or shape of the grate described in said patent is circular, and my present invention relates to means whereby I am enabled to use substantially the same principle of construction there- 25 in described in a rectangular or square grate; and it consists in various details of construction whereby this result is accomplished.

Referring to the drawings, A represents the grate-frame; a , the front and rear bars of the 30 main grate; a' , the end bars thereof. These front and back and end bars are pivoted to each other at a^2 , and the end bars are pivoted to the grate-frame A and to the cross-piece or plate a^3 at a^4 . Each of the grate-bars has 35 projections or fingers a^5 , extending downwardly and inwardly to the opening B. The corner fingers, a^6 , are shaped as represented in Fig. 1, so that the movement of the grate cannot be interfered with by means of coals or 40 cinders lodging between the fingers at the corners. By means of the lever or arm B' , or in any other desirable way, the grate is recipro- 45 cated laterally upon the pivots a^4 . This causes each of the back and front and of the end bars to be moved in opposite directions, and a very ef- fective shaking action is thus provided. Of course, the opening B may be nearer the back of the grate, as represented in the drawings, or it may be centrally located, or at the front. I 50 prefer generally, however, as the front portion of the fire is more easily reached by the

poker, to make the fingers upon the back bar more inclined than those upon the front, there- 55 by throwing the opening B toward the back, as by so doing a smaller support is provided for the fire at the back, and consequently, upon a reciprocation of the grate, the ashes at that portion of the fire will settle more rapidly upon the under grate, and thus clear the fire more quickly than if the fingers or 60 projections were longer and less inclined, and the back of the fire will therefore require less attention.

Below the opening B, I arrange the under grate, C, which may be solid, as represented 65 in the drawings, or may have openings across it. It preferably is pivoted to dump toward the front of the ash-pit, and it is supported by the cross-bar or rod b , the ends of which form pivots b' , which are supported by the 70 brackets b^2 , attached to the grate-frame. This grate is dumped or turned by means of a lever attached to one end of the rod b , and an arm which extends from the end of the lever, pref- erably to without the stove, through a slot in 75 the casing, or in any other desirable way.

Between the lower and the upper grate is the anti-clinker space D. There may be ar- ranged between the bars a a' of the grate and 80 the grate-frame a space, e, so that the upper and lower surfaces of the end and back bars shall not come in contact therewith, in which case the frame may have projections e' , extending downwardly and upwardly therefrom that shall come in contact with the upper and 85 lower surfaces of the grate-bars.

I do not confine myself to the especial means for connecting or pivoting together the ends of the bars; neither do I limit myself to the exact method of hanging it specified, and I 90 may use any mechanical equivalents for the specific methods herein described without de- parting from the spirit of the invention. It is of course obvious that by reducing the size of the opening in the upper grate the lower grate 95 may be entirely dispensed with; but I do not prefer this construction.

In Figs. 4 and 5 the fingers a^5 of the upper grate are shown extended very nearly across the opening B, and they may be shaped as 100 shown in Fig. 3—that is, the upper portion thereof may be inclined and the lower portion

horizontal, as desired, or they may be entirely inclined or horizontal. This construction enables me to dispense with the lower section, 'C, of the grate.

5 I am aware of the Patent No. 34,731, to Brown, dated May 25, 1862, and I do not claim anything therein described; nor do I consider that it contains the features of my invention, in that it does not describe a grate 10 having four bars pivoted together at their ends and to the grate-frame, as above described, and having fingers which project inward therefrom to form the fire-supporting surface. It will be noticed that this construction divides 15 the grate into four sections—namely, the front and back and the two end—and that each section has a movement in a direction the reverse of the movement of the one opposite it, and that, therefore, by this movement, the fire is 20 well-broken and shaken at the end as well as at the center.

Having thus fully described my invention, I claim and desire to secure by Letters Patent of the United States—

25 1. A stove-grate having the parallel side bars, a , and the parallel end bars, a' , the end bars being pivoted to the frame of the grate, as described, and the side bars being pivoted to the end bars at a^2 , the said bars having the 30 fingers a^5 projecting inwardly therefrom, all substantially as and for the purposes described.

2. A stove or furnace provided with a rectangular or square grate, consisting of the fingered bars a a' , surrounding the opening B, adapted to be reciprocated, as specified, and 35 the grate C below said opening B, capable of being tipped toward the ash-pit door, and a clearing-space, D, between the upper surface and the lower surface of the upper grate, substantially as and for the purposes specified. 40

3. The combination, in a grate, of the fingered grate-bars a a' , pivoted to each other and to the grate-frame, as specified, surrounding the opening B, and adapted to be moved or reciprocated in relation to each other as indicated, with the grate C below said opening B, all substantially as and for the purposes 45 described.

4. In a grate, the combination of the fingered bars a a' , pivoted to each other and to the grate-frame surrounding the opening B, the fingers of the back bar being more inclined than those of the front, and adapted to be moved or reciprocated in relation to each other as indicated, with the grate C, arranged below said 50 opening B, all substantially as and for the purposes described. 55

EDGAR W. ANTHONY.
